UNITED STATES PATENT OFFICE.

ERNEST OLDENBUSCH, OF NEW YORK, N. Y.

MATCH-BOX AND CIGAR-CUTTER.

1,186,328.

Specification of Letters Patent.

Patented June 6, 1916.

Application filed December 7, 1915. Serial No. 65,491.

To all whom it may concern:

Be it known that I, ERNEST OLDENBUSCH, a citizen of the United States, and a resident of the city of New York, borough of Brooklyn, in the county of Kings and State of New York, have invented a new and Improved Match-Box and Cigar-Cutter, of which the following is a full, clear, and exact description.

10 The invention relates to a combined match box and cigar cutter and has for an object the provision of an improved arrangement whereby a package of matches is held properly in position and properly protected 15 while certain parts of the device may be utilized for cutting and severing the end of a cigar.

Another object in view is to provide a box formed in parts and arranged with 20 turned-over ears for receiving packages of matches, these members being arranged in connection with a catch or retaining member which acts in the double capacity of a catch and retaining member for parts of 25 the box and also acts as a cutter when the parts are being closed.

In the accompanying drawings:—Figure 1 is a perspective view of a box embodying the invention, the parts thereof being shown 30 open; Fig. 2 is a top plan view of the structure shown in Fig. 1, the same being shown closed; Fig. 3 is a section through Fig. 2 on line 3—3; Fig. 4 is an edge view of the structure shown in Fig. 2; Fig. 5 is a side view of the upper part of the structure 35 shown in Fig. 2.

Referring to the accompanying drawings by numerals, 1 indicates the box as a whole, which is divided into sections 2 and 3 connected together by a hinge 4. Section 2 acts 40 as the body of the box while section 3 acts as the lid. The section or body 2 is provided with ears or retaining members 5 and 6 for receiving the ends 7 of the matches 8 whereby the matches are properly held in 45 the box. The matches 8 do not extend to the top of the body 2, whereby a space is provided for receiving the end of a cigar when the device is used as a cigar cutter.

50 In order to use the device as a cigar cutter body 2 is provided with a pressed-up V-shaped portion 9 having an aperture 10 arranged therein whereby this portion is somewhat resilient but acts with the V-shaped projection 11 as means for cutting a cigar, as shown in Fig. 3, and also as

means for retaining the lid or section 3 in a closed position. The parts are so proportioned that the pressed-out portion 11 presses against the resilient pressed-up portion 9 so that the friction created by these parts pressing against each other causes these parts to act as a catch for holding the box closed, as shown in Fig. 4.

In operation, when it is desired to use the 65 box the same may be opened by pulling against the sections 2 and 3 so that the parts will be moved from the position shown in Fig. 4 to that shown in Fig. 1. A match is then removed and if it is desired to light 70 a cigar the end of the cigar is passed through the aperture 10 and then lid 3 is closed. The closing of lid 3 causes the pressed-out portion 11 acting with member 9 to sever the end of the cigar. In this way 75 the cigar will be cut and the box will be locked in a closed position simultaneously. The match may then be used in the usual manner for lighting the cigar or other purpose. 80

What I claim is:

1. In a device of the character described, a body and a lid, means for hinging said body and lid together, said body being provided with a V-shaped pressed-out portion 85 and said lid being provided with a complementary V-shaped pressed-out portion adapted to fit the pressed-out portion on the body and act in the double capacity of a cigar cutter and a catch for holding the lid 90 closed.

2. A match box and cigar cutter comprising a body provided with means for clamping a package of matches therein, a lid hinged to said body, said body being formed 95 with an apertured projection and said lid being provided with a projection coacting with the projection on the body and acting as a cutting member when moved across the apertured projection when the lid is closed 100 for severing a cigar extending through said apertured projection.

3. In a device of the character described, a body, a lid hinged thereto, said body being provided with an apertured pressed-out 105 portion, and a solid pressed-out portion arranged on said lid and adapted to slidingly fit against the apertured pressed-out portion and to overlap the aperture thereof, whereby a cigar passing through the aperture of said 110 apertured portion will be severed when the lid is closed.

4. In a device of the character described, a body provided with a V-shaped pressed-out portion having an aperture arranged substantially centrally of the V whereby
5 said V will be somewhat resilient, and a cap provided with a V-shaped cutting member pressed up therefrom, said cutting member being of substantially the same shape as said V-shaped pressed-out portion and ar-
10 ranged to slide thereunder and cut a cigar extending therethrough, the resiliency of

said apertured pressed-out portion acting against the cutter for producing a retaining structure for holding the cap closed in ad-
dition to a cutting structure.

15

In testimony whereof I have signed my name to this specification in the presence of two subscribing witnesses.

ERNEST OLDENBUSCH.
